Primary Examiner — Sandra Snapp*Assistant Examiner* — Ieisha Price(74) *Attorney, Agent, or Firm* — Honigman Miller Schwartz and Cohn LLP(57) **CLAIM**

The ornamental design for a clutch cover for roller blind, as shown and described.

DESCRIPTION

FIG. 1 is a front/right side isometric view of an embodiment of a clutch cover for roller blind;

FIG. 2 is a front view of the embodiment of FIG. 1;

FIG. 3 is a rear view of the embodiment of FIG. 1;

FIG. 4 is a right side elevational view of the embodiment of FIG. 1;

FIG. 5 is a left side elevational view of the embodiment of FIG. 1;

FIG. 6 is a top view of the clutch cover for roller blind of the embodiment of FIG. 1; and,

FIG. 7 is a bottom view of the clutch cover for roller blind of the embodiment of FIG. 1.

1 Claim, 7 Drawing Sheets(56)
